UNITED STATES PATENT OFFICE.

CLAUDE EDWIN MENTZER, OF DES MOINES, IOWA, ASSIGNOR OF ONE-HALF TO CARL B. SMITH, OF DES MOINES, IOWA.

ANTIGLARE SHIELD FOR HEADLAMPS.

Application filed January 15, 1926. Serial No. 31,414.

The object of this invention is to provide an improved anti-glare shield for automobile head lamps and the like.

A further object of this invention is to provide an anti-glare shield for head lamps that will fit any size of head lamps and may be attached or detached in a moment's time without harm to the lamp.

A further object is to provide an anti-glare shield that is simple in construction and economical in manufacture.

More specifically the object of this invention is to provide an anti-glare shield designed to be mounted on the electric light socket of the lamp and to outwardly and forwardly extend therefrom in vertical steps.

A further object is to provide a means for keeping the steps in vertical position.

These and other objects will be apparent to those skilled in the art.

My invention consists in the construction, arrangement and combination of the various parts of the device, whereby the objects contemplated are attained as hereinafter more fully set forth, pointed out in my claims and illustrated in the accompanying drawings, in which:

Fig. 1 is a perspective view of my complete anti-glare shield ready for use.

Fig. 2 is a front view of my device mounted on a head lamp.

Fig. 3 is a top plan sectional view of my device mounted on a head lamp and is taken on line 3-3 of Fig. 2.

Many accidents fatal to life and property are caused by blinding head lamps. Devices now on the market for preventing the blinding light are costly and are confined chiefly to the construction of the lens of the lamp which are easily broken. My device deals with the reflecting of the light and is stamped from one piece of inexpensive sheet metal.

I have used the numeral 10 to designate the bowl or body portion of an electric lamp, having the lens 11 and reflector 12. Mounted in the bowl 10 and extending through a hole 13 in the reflector 12 is the electric light socket 14 having lead wires 15 and 16. Mounted in this socket and in front of the reflector 12 is the incandescent light bulb 17. I have designated my anti-glare shield generally by the number 18. It is almost circular except for two large notches in its sides. These notches are diametrically opposite one from the other. In the center of

my device is a hole 19 which is designed to embrace the socket 14. From this socket my device extends outwardly and forwardly in vertical steps until the ends or ears 20 and 21 engage the reflector 12. As these ends are rounded they are capable of conforming to the curvature of the reflector and thereby make proper engagement therewith. This engagement is not essential but does act to stabilize the device in the lamp. On lamps that have very large reflectors the ends would not perhaps touch the reflector at all. As before stated the device is capable of being stamped from a piece of sheet metal and in so doing it is well to leave two tongues 22 and 23 extending into the hole 19. These tongues are designed to be bent around the marginal edge of the hole 13 in the reflector 12, as shown in Fig. 3. They aid in holding the shield in the lamp and prevent the same from turning from the position shown in Fig. 2. From this figure it will be noted that the two notches before mentioned are directly above and below the bulb 17, respectively, or in other words the shield becomes larger as it extends laterally from the bulb 17. Neither the outwardly and rearwardly extending walls 24 or the forwardly and outwardly extending walls 25 that make up the steps are parallel with the axis of the bulb 17, but are at an angle thereto, as will be noted in Fig. 3. As the shield is in front of the reflector 12 and is preferably polished or nickel plated it becomes a reflector, but because of the steps it does not reflect the light as the reflector 12 into a focus or spot of light, but diffuses and sprays the light. This however is not true when in a direct line in front of the bulb 17 as the shield is restricted at its center and therefore does not shield the reflector 12 just above and below the bulb 17. By this arrangement there is a condensed spray of light directly in front of the lamp, but a few degrees on either side of this condensed light, the shield becomes the reflector and the light is diffused and not blinding. This means that when automobiles use my invention and when passing each stays on its side of the road, respectively, and are not in direct line, there will be no blinding lights to affect the drivers of the automobiles.

Another advantage of my invention resides in the fact that it throws a glow of light to the side so that the driver can see pedestrians at the intersection of streets.

To remove my device from the lamp, remove the bulb 17 and unbend the tongues 22 and 23.

Some changes may be made in construction and arrangement of my improved anti-glare shield for head lamps without departing from the real spirit and purpose of my invention and it is my intention to cover by my claims and modified forms of structure 10 or use of mechanical equivalents which may be reasonably included within their scope.

I claim:

1. In a device of the class described, a plate member having a hole near its center 15 designed to embrace the electric light socket in a head lamp, vertical steps on said plate member, said plate member having a V notch in its upper portion and a V notch in its lower portion, for the purposes stated.
2. In combination with a head lamp, a device comprising a plate having a hole designed to embrace the electric light socket in the said lamp, outwardly and forwardly extending walls formed on said plate, said 25 plate member having a V notch in its upper portion and a V notch in its lower portion.
3. In a device of the class described, a plane central body portion having a hole, forwardly and outwardly extending walls 30 on each side of said central portion, outwardly and rearwardly extending walls on each side of said central portion; said forwardly and outwardly extending walls being alternated with said outwardly and rearwardly extending walls, and tongues for holding the device to the reflector of a head lamp.
4. In a device of the class described, a plane central body portion having a hole, 35

forwardly and outwardly extending walls 40 on each side of said central portion, outwardly and rearwardly extending walls on each side of said central portion; said forwardly and outwardly extending walls being alternated with said outwardly and 45 rearwardly extending walls, and said walls terminating on each side of said central portion in a circular marginal edge designed to engage the reflector of a head lamp.

5. In combination with a head lamp having 50 a reflector and an electric light socket extending through a hole in said reflector, a device comprising a central body portion having a hole designed to embrace said socket, tongues on the marginal edge of said 55 hole in the central body portion for embracing the marginal edge of the hole in said reflector, forwardly and outwardly extending walls on each side of said central portion, outwardly and rearwardly extending 60 walls on each side of said central portion, said outwardly and rearwardly extending walls being alternated with said forwardly and outwardly extending walls, said walls nearest said central portion being shorter in 65 length than those more remote, and a flange having a circular marginal edge formed on the last extending wall on each side of the central body portion designed to conform to and engage the inside of the said reflector. 70

6. As a new article of manufacture, an anti-glare shield for headlights comprising a plane body portion and integral wings extending laterally therefrom and formed with successive steps vertically arranged at 75 right angles to each other and oblique to the axis of the headlight.

CLAUDE E. MENTZER.
